UNITED STATES PATENT OFFICE

123,426

DESIGN FOR A COMBINATION PRESSING AND STEAMING IRON

Frank E. Wolcott, West Hartford, Conn., assignor
to The Silex Company, Hartford, Conn., a cor-
poration of Connecticut

Application August 16, 1940, Serial No. 94,449

Term of patent 14 years

To all whom it may concern:

Be it known that I, Frank E. Wolcott, a citizen
of the United States, residing at West Hart-
ford, in the county of Hartford and State of
Connecticut, have invented a new, original, and
ornamental Design for a Combination Pressing
and Steaming Iron, of which the following is a
specification, reference being had to the accom-
panying drawing, forming part thereof.

Fig. 1 is a top plan view of a combination

pressing and steaming iron embodying my new
design.

Fig. 2 is a side elevational view thereof.

Fig. 3 is a front elevational view.

Fig. 4 is a rear elevational view.

I claim:

The ornamental design for a combination
pressing and steaming iron, substantially as
shown.

FRANK E. WOLCOTT.
